UNITED STATES PATENT OFFICE.

ERICH H. LICHTENBERG, OF MILWAUKEE, WISCONSIN, ASSIGNOR TO KOEHRING MACHINE COMPANY, OF MILWAUKEE, WISCONSIN.

CONTROL MECHANISM FOR CONCRETE-MIXERS.

1,103,788.

Specification of Letters Patent. Patented July 14, 1914.

Application filed October 25, 1913. Serial No. 797,256.

To all whom it may concern:

Be it known that I, ERICH H. LICHTENBERG, a citizen of the United States, residing at Milwaukee, in the county of Milwaukee, 5 and State of Wisconsin, have invented certain new and useful Improvements in Control Mechanism for Concrete-Mixers, of which the following is a specification.

This invention appertains to portable 10 mixing machines and comprises essentially certain novel control mechanism whereby the power of a suitable motor mounted on the machine may be readily utilized for causing forward and rearward travel of the 15 machine on its wheels, for raising and lowering a charging bucket or equivalent device by which the mixing drum is supplied with the materials to be mixed, and for driving the said drum.

For a full understanding of the present 20 invention, reference is to be had to the following description and to the accompanying drawings, in which—

Figure 1 is a side view of a concrete 25 mixer of the portable or wheeled type, showing the invention as used in connection therewith. Fig. 2 is a plan view showing the frame of the machine broken away and illustrating more in detail the various parts of 30 the control mechanism. Fig. 3 is a fragmentary front view showing more clearly the arrangement of the driving and controlling gears. Fig. 4 is a fragmentary view in section bringing out more clearly the connection 35 intermediate the winding drum and its associated driving gear or element.

Throughout the following detail description and on the several figures of the drawings, similar parts are referred to by like 40 reference characters.

The machine illustrated may be said to be of a conventional type, so far as the purposes of the invention are concerned, a controlling mechanism as hereinafter detailed being 45 susceptible of use in connection with various kinds of mixers involving the general features of a portable truck, mixing drum and charging bucket.

In the drawings A denotes the truck which 50 is supported on the front and rear wheels 1 and 2 respectively, suitable steering mechanism, not shown, being supplied for the first mentioned wheels.

B is a motor, a steam or explosive engine,

preferably, C a mixing drum and D a 55 bucket for charging said drum C.

The range of movement of the bucket D is indicated by the full and dotted lines in Fig. 1, and the operating means for the bucket includes primarily suitable cables 3 60 connected at one end with the bucket D and passing over sheaves 4 on the framework 5 of the machine. The cables 3 extend to drums 6 on the shaft 7 and are adapted to wind about said drums. An operating cable 65 8 connects the shaft 7 with the motor B, under the control of the mechanism now to be set forth, and said cable passes about a large drum 9 on the shaft 7 and around the small drum 10 loosely mounted upon a shaft 1 supported in suitable bearings on the truck A. 70

The engine shaft 12 carries a gear 13 which meshes with a corresponding gear 14 on the shaft 11, power being thus transmitted from the engine to the shaft 11. 75

As previously suggested, the drum 10 is loosely mounted on the shaft 11, being directly carried by a clutch sleeve which passes through the drum and is journaled on said shaft. Gears 15 and 16 are keyed or otherwise secured to the clutch sleeve 17 aforesaid and are located on opposite sides of the drum 10 which is loose on said sleeve. The clutch sleeve 17 carries the usual clutch housing 18 about which a brake band 19 80 passes, and clutch dogs 20 of a conventional type, operable by a lever 21, coöperate with the part 18. 85

On a countershaft 22 located adjacent to the shaft 11 is mounted a gear 23 shiftable by a lever 24 into mesh with the gear 15. The gear 23 is also adapted to mesh with a small reversing gear 25 journaled above the shaft 22 and normally in mesh with the gear 16. At its rear end the shaft 22 carries a bevel pinion 26 that meshes with a bevel gear 27 on a transverse shaft 28 mounted on the frame of the truck A in any suitable manner. The shaft 28 carries sprocket wheels 29 that are connected by the sprocket drive 100 chains 30 with large sprockets 31 secured to the rear wheels 2 of the truck A. A feather and spline connection 32 is preferably provided intermediate the shaft 22 and the gear 23. 95 105

On the gear 15 is mounted a transversely slidable pin 33 movable by the operation of a lever 34 into and out of engagement with

an opening in the drum 10. It is by this means that the drum 10 may be connected and disconnected from the engine B in a manner which will now be more fully described.

5 In the normal operation of the machine for mixing purposes, it being understood that the shaft 11 is supplied with driving gears 35 engaging gear rings 36 on the drum C, it will be apparent that the drum C is readily rotatable by the engine. When it is desired to raise the bucket D for the purpose of charging the drum C the operator by manipulating the lever 34 will engage the pin 33 with the drum 10, whereupon a driving 10 connection between the shaft 11 and the drum may be established by the mere operation of the clutch lever 21. When the bucket D has been raised into the dotted line position in Fig. 1, the lever 21 will, of course, be moved to the left, as shown in Fig. 2, and the brake band 19 applied so as to discontinue the upward movement of the bucket D. The bucket may then be gradually lowered by controlling the reverse rotation of the drum 10 by means of the lever 37 which is connected with the brake band 19.

When it is desired to adjust the gearing above described, for traction purposes, it is only necessary to shift the lever 24 in one direction in order to engage the gear 23 with the gear 15, whereupon the operation of the clutch lever 21 will cause the shaft 22 to be driven and from this shaft power is transmitted to the driving wheels 2 through the pinion 26, gear 27, shaft 28 and sprocket chain connections 30. In the above manner the machine may be caused to travel forwardly. If it is desired to cause a reverse or rearward movement of the machine the lever 24 is shifted so as to carry the gear 23 into mesh with the reverse gear 25, whereupon on operation of the lever 21 to properly actuate the clutch mechanism, power is transmitted from the shaft 11 to the shaft 22 in a reverse direction to that before described, through the gears 16 and 25.

It will of course be understood that when the gearing is being operated for traction purposes the lever 34 will have been previously operated so as to disconnect the gear 15 from the drum 10. In fact, the parts 10 and 15 are only connected when the bucket D is to be operated.

The mechanism above described is very simple and compactly arranged and affords an extremely effective and desirable control for machines of the class described.

The means hereinbefore referred to for connecting the gear 15 with the drum 10, and including the parts 33 and 34, may be seen clearly in Fig. 4 of the drawings. As shown in this figure the lever 34 is adapted for rotary movement to thereby engage with a cam 15^a carried by the gear 15. By such engagement the lever 34 is caused to move out-

ward with respect to the gear 15 and thereby pull outwardly upon the pin 33 which is normally pressed inward by a coiled spring 33^a bearing thereagainst. When the member 34 has been adjusted to the dotted line position in Fig. 4 it will be obvious that the pin 33 is entirely disengaged from the drum 10 and the driving connection intermediate the parts 15 and 10 thus interrupted. On the other hand, by moving the lever 34 from its dotted line position to its full line position the spring 33^a is permitted to act on the pin 33 to engage the same with the drum 10.

Having thus described the invention, what is claimed as new is:—

1. In a machine of the class described, the combination of a driven shaft, a clutch sleeve on said shaft, means for clutching said sleeve to the shaft, a winding drum loosely mounted on said clutch sleeve, a plurality of gears connected with the clutch sleeve for rotation therewith, a hoisting cable adapted to wind about said drum, a shiftable gear, means for shifting said shiftable gear into operative connection with the first mentioned gears, and means for connecting one of the first mentioned gears with the winding drum whereby to transmit motion from the said driven shaft to the winding drum. 80

2. In a machine of the class described, the combination of a driven shaft, a clutch sleeve on said shaft, means for clutching said sleeve to the shaft, a winding drum loosely mounted on said clutch sleeve, a plurality of gears connected with the clutch sleeve for rotation therewith, a hoisting cable adapted to wind about said drum, a shiftable gear, means for shifting said shiftable gear into operative connection with the first mentioned gears, and means for connecting one of the first mentioned gears with the winding drum whereby to transmit motion from the said driven shaft to the winding drum. 85

90

2. In a machine of the class described, the combination of a driven shaft, a clutch sleeve on said shaft, means for clutching said sleeve to the shaft, a winding drum loosely mounted on said clutch sleeve, a plurality of gears connected with the clutch sleeve for rotation therewith, a hoisting cable adapted to wind about said drum, a shiftable gear, means for shifting said shiftable gear into operative connection with the first mentioned gears, and means for connecting one of the first mentioned gears with the winding drum whereby to transmit motion from the said driven shaft to the winding drum. 95

100

2. In a machine of the class described, the combination of a driven shaft, a clutch sleeve on said shaft, means for clutching said sleeve to the shaft, a winding drum loosely mounted on said clutch sleeve, a plurality of gears connected with the clutch sleeve for rotation therewith, a hoisting cable adapted to wind about said drum, a shiftable gear, means for shifting said shiftable gear into operative connection with the first mentioned gears, and means for connecting one of the first mentioned gears with the winding drum whereby to transmit motion from the said driven shaft to the winding drum, a reversing gear intermediate the shiftable gear and one of the first mentioned gears whereby to obtain reverse action, and means for retarding the movement of the winding drum. 105

110

3. Control mechanism for mixing machines comprising, in combination, a motor driven shaft, clutch mechanism including a clutch member having a clutch sleeve mounted on said shaft, means for clutching said clutch member to the shaft for rotation therewith, a winding drum loose on the said clutch sleeve, gears fixed to said sleeve, means for connecting one of the gears with the winding drum, a drive shaft, a shiftable gear connected with said shaft, and means for moving said shiftable gear to engage the same with either one of the first mentioned gears to transmit motion to the drive shaft. 115

120

3. Control mechanism for mixing machines comprising, in combination, a motor driven shaft, clutch mechanism including a clutch member having a clutch sleeve mounted on said shaft, means for clutching said clutch member to the shaft for rotation therewith, a winding drum loose on the said clutch sleeve, gears fixed to said sleeve, means for connecting one of the gears with the winding drum, a drive shaft, a shiftable gear connected with said shaft, and means for moving said shiftable gear to engage the same with either one of the first mentioned gears to transmit motion to the drive shaft. 125

130

4. Control mechanism for mixing machines comprising, in combination, a motor driven shaft, clutch mechanism including a clutch member having a clutch sleeve mounted on said shaft, means for clutching said clutch member to the shaft for rotation therewith, a winding drum loose on the said clutch sleeve, gears fixed to said sleeve, means for connecting one of the gears with the winding drum, a drive shaft, a shiftable gear connected with said shaft, and means for moving said shiftable gear to engage the same with either one of the first mentioned gears to transmit motion to the drive shaft. 135

clutch member having a clutch sleeve mounted on said shaft, means for clutching said clutch member to the shaft for rotation therewith, a winding drum loose on the said 5 clutch sleeve, gears fixed to said sleeve, means for interlocking one of said gears with the winding drum at will whereby the drum will rotate with the clutch sleeve, a drive shaft, and means intermediate said 10 gears and the drive shaft for transmitting forward and reverse motion to the latter.

5. Control mechanism for mixing machines comprising, in combination, a motor driven shaft, clutch mechanism including a 15 clutch member having a clutch sleeve mounted on said shaft, means for clutching said clutch member to the shaft for rotation therewith, a winding drum loose on the said clutch sleeve, gears fixed to said sleeve, 20 means for interlocking one of said gears with the winding drum at will whereby the drum will rotate with the clutch sleeve, a drive shaft, means intermediate said gears and the drive shaft for transmitting 25 forward and reverse motion to the latter, and a brake band coöoperating with the clutch member to retard the movement of the drum in one direction after release of the clutch member from the driven shaft.

30 6. In control mechanism of the class described, the combination of a driven shaft, a clutch member mounted on said shaft, means for clutching said member to the shaft, gears connected with the clutch member, a drum supported on the shaft, manually operable means for connecting said 35 drum with one of the gears aforesaid, a drive gear, a reversing gear engaging one of the first mentioned gears, and means for 40 shifting said drive gear into engagement with the other of the first mentioned gears, or the reverse gear.

7. In control mechanism of the class described, the combination of a driven shaft, 45 a clutch member mounted on said shaft, means for clutching said member to the shaft, gears connected with the clutch member, a drum supported on the shaft, manually operable means for connecting said 50 drum with one of the gears aforesaid, a drive shaft and drive gear, a reversing gear engaging one of the first mentioned gears, and means for shifting said drive gear into engagement with the other of the first mentioned 55 gears, or the reverse gear, whereby forward and reverse motion may be imparted to the drive shaft aforesaid, the clutch member above mentioned comprising a sleeve supporting the first mentioned 60 gears and carrying between said gears the winding drum above referred to.

8. In control mechanism of the class described, the combination of a driven shaft,

a clutch member mounted on said shaft, means for clutching said member to the 65 shaft, gears connected with the clutch member, a drum supported on the shaft, means for connecting said drum with one of the gears aforesaid, a drive shaft and drive gear, a reversing gear engaging one of the first 70 mentioned gears, and means for shifting said drive gear into engagement with the other of the first mentioned gears, or the reverse gear, whereby forward and reverse motion may be imparted to the drive shaft 75 aforesaid, the clutch member above mentioned comprising a sleeve supporting the first mentioned gears and carrying between said gears the winding drum above referred to.

80 9. Control mechanism for mixing machines comprising, in combination, a motor driven shaft, clutch mechanism including a clutch member, mounted on said shaft, means for clutching said clutch member to 85 the shaft for rotation therewith, a winding drum loose on said motor driven shaft, a gear fixed to said clutch member, means for interlocking said gear with the winding drum, a drive shaft, a shiftable gear connected with said shaft, and means for moving said shiftable gear to engage the same 90 with the first mentioned gear to transmit motion to the drive shaft.

95 10. Control mechanism for mixing machines comprising, in combination, a motor driven shaft, clutch mechanism including a clutch member, mounted on said shaft, means for clutching said clutch member to the shaft for rotation therewith, a winding drum loose on said motor driven shaft, a gear fixed to said clutch member, means for interlocking said gear with the winding drum, a drive shaft, a gear connected with 100 said shaft, and means for engaging said gear with the first mentioned gear to transmit motion to the drive shaft.

110 11. Control mechanism for mixing machines comprising, in combination, a motor driven shaft, clutch mechanism, including a clutch member having a clutch sleeve, mounted on said shaft, means for clutching said clutch member to the shaft for rotation therewith, a winding drum loose on the said clutch sleeve, a gear fixed to said sleeve, means for connecting said gear with the winding drum, a drive shaft, and means for 115 communicating motion to said drive shaft by engagement with the gear on said clutch sleeve.

120 In testimony whereof I affix my signature in presence of two witnesses.
